OBSTRUCTION LIGHTING STRUCTURE

Filed Feb. 22, 1945

FIG. 1

FIG. 3.

FIG. 2

INVENTOR.

CLYDE K. LAMB

BY

UNITED STATES PATENT OFFICE

2,498,556

OBSTRUCTION LIGHTING STRUCTURE

Clyde K. Lamb, Cleveland, Ohio, assignor by
direct and mesne assignments, to Lamb &
Chapin, Incorporated, Cleveland, Ohio, a cor-
poration of Ohio

Application February 22, 1945, Serial No. 579,292

2 Claims. (Cl. 240—2)

1

My invention relates to obstruction lighting structures and relates more particularly to the provision of a permanent lighting structure adapted to circumscribe a chimney or stack and carrying lights which are visible both from the ground and from the air and which are particularly useful in warning approaching aircraft of the presence of such stack or chimney structures.

My invention further relates to obstruction lighting structures of the type described combining the provision of a permanent lighting structure with a guard rail structure adapted to protect workmen engaged in servicing the obstruction lights carried thereby.

Another object of my invention relates further to the provision of obstruction lighting structures of the type described wherein the lights may be easily serviced.

Another object of my invention is to provide obstruction lighting structures of the type referred to incorporating therein means whereby said lights may be easily cleaned by remote control, preferably located at ground level.

Other objects of my invention and the invention itself will become increasingly apparent by reference to the following description of embodiments of my invention and to the drawings thereof, in which drawings:

Fig. 1 is a top plan view, partially in section, certain portions being broken away so that other parts may be more fully illustrated, of the lighting structure of my invention as applied to a circular stack;

Fig. 2 is a side elevational view of the lighting structure of Fig. 1, said view having certain portions broken away;

Fig. 3 is a front plan view of the embodiment of Figs. 1 and 2 but showing another modification of such design.

Referring now to the drawings, in all of which like parts are designated by like reference characters, at Fig. 1 I have indicated generally the obstruction lighting structure of my invention, this lighting structure consisting of three light-carrying mountings, A, B and C, and a pair of reinforcing members, D and E. It will be obvious that, according to the size of the stack or chimney upon which such lighting structure is carried, the number of lighting structures warning of the presence of such air obstruction to aircraft and the like, may be varied and hence the number of reinforcing members may be increased. Such reinforcing members may further be eliminated, if desired.

In normal scaffold construction employed in creating a staging for work on chimneys, etc., a pair of metallic bands 3 and 4 are adapted to be telescoped about the entire circumference of the stack or chimney 5, said bands being spaced a substantial distance apart and being disposed about the entire circumference of the stack or chimney 5 at the height at which the structure is to be positioned. A preferred spacing between the bands in my invention is about 40". Each of the metallic bands 3 and 4 are preferably further, as best shown in Fig. 1, composed of a plurality of similar metal bands secured together by couplings which are bolted together wherefore the bands are tightly secured to the chimney or stack structure and the light-carrying devices, A, B and C, and the reinforcing members D and E are rigidly secured thereto.

It will be noted that a plurality of U-shaped step members 30 are disposed over the band, said steps being provided with downwardly extending portions 31 disposed between the bands 4 and the chimney structure, a hooked end portion 32 of each locking the step to the band and preventing the disengagement of the step therefrom.

A plurality of hand grip members 30', aligned with said step and having downwardly extending portions 31' ending in upwardly disposed end hook portions 32' and similarly formed to the step members 30, are disposed between the upper band 3 and the chimney or stack. These hand grip and step members are similar to those described and claimed in Patent No. 2,358,014 of this applicant.

The improved obstruction lighting structure of my present invention is preferably embodied in a combined back rail and loop structure which is formed in the following manner:

A plurality of loops 10, preferably tubular and cylindrical in form and comprising a relatively long stem portion 20 and a curved head portion 22, is adapted to be secured to the bands 3 and 4 and to carry a guard rail structure at a point spaced from the chimney, the curved head portion extending outwardly from and above the height of the upper band 3.

The stem portion is disposed between the bands 3 and 4 and the chimney, lying substantially flush therewith and said stem portion 20 terminates in a hooked end portion 21 curved about the lower band portion 4 whereby it is rigidly secured thereto.

The outwardly extending head portion 22 terminates in an outwardly disposed upwardly hooked

end portion 23 upon which a rectangular cross member 24 is carried, said member 24 supporting the light fixtures, generally indicated at 25.

A conduit 26 outwardly spaced from the cylindrical stack a suitable distance and forming an outer cylindrical band and guard rail structure encompassing such stack is adapted, in the form of my invention shown in Figs. 1 and 2, to be disposed beneath the cross members 24 passing through the hooked end portion 23 of the light carrying loop structure.

It is to be noted that in the form of Figs. 1 and 2 and according to the size of the stack there employed, three of such light carrying structures are provided and that the conduit is continuous beginning at the structure B, passing through the structure A, and terminating in the structure C.

The reinforcing members D and E are formed similarly to the loop structures carrying the light fixtures with the exception that the stem portion thereof is not of such length as to extend through the band 4 but terminates in a turned in hooked end portion 28 disposed over the outer face of the cylindrical band 3 and an opposite hooked end portion 29, secured to the conduit 26, as by welding or the like.

The lighting support structure A consists in a step 40 adapted to be pivotally secured, as at 41, to a ladder secured to the stack and projecting through the structure A, as shown in Figs. 1 and 2. The rearward portion of the step 40 when "down" is adapted to rest upon a pair of diagonally disposed members 42 carried by opposite sides of the ladder structure, and to be secured to the ladder by a hook 43 when in its inoperative "up" position whereby it is locked against the ladder structure in such position.

The looped overhead portion 22 of the light carrying structure shown as A is adapted to be projected between a pair of adjacent rungs of the ladder and centrally of said ladder at a point midway between the sides thereof whereby the ladder may be utilized by workmen desiring to use the same to ascend to the top of the stack structure.

Also, it is to be noted that, as best shown in Fig. 1, the lighting fixtures carried by the cross member of the said structures A, B and C, preferably comprise a pair of 100-watt lamps, or lamps of whatever power be desired, said lamps being mounted in the form shown upon a conduit box 50, receiving current through a cable carried by the conduit 51, said cable being brought up the chimney adjacent the ladder and passing through the portion 22 to the lights at stations A, B and C.

An air conduit 69 further disposed adjacent the ladder is brought up the chimney and disposed within the portion 22 of the structure at A, traveling across the cross member 24 from whence the conduit branches off to a pair of narrow tubes, preferably of copper, 70-70, a pair of each of these being placed about each of the lamps and spaced therefrom, said tubes being bowed at their upper ends in the manner shown in my aforesaid patent and having each an open jet 71 through which the air is blown from remote control means mounted at ground level with sufficient force directed at the convex head of the lamp to thoroughly clean the same.

A ring member 72 is secured about the lower ends of the bowed tubes 70-70 to retain the same in place as by a clamp member.

The air conduit proceeds to structure B and C 75

through the conduit 26 to clean the lamps thereat disposed through jets 71 thereof.

Since the air pressure is operated from remote control means mounted upon the ground or at a lower position on the stack, the lights may be cleaned therefrom, eliminating the necessity of a workman climbing the stack and cleaning the same, but in the event that a lamp structure needs replacement or repair, it will be necessary for a workman to ascend the ladder 9 and to travel about the chimney at the stage of mounting.

To secure this desired movement, the workman walks about the outer periphery of the chimney and at all times in his travels from the light carrying structure A to B, or from B to A or A to C or C to A etc., is protected by the conduit 26 acting as a back guard rail member.

The steps 40 which are disposed in connection with the light carrying structures A, B and C, and positioned as above described with respect to the structure A, are hinged at stations B and C to a step 30" similar to the other steps 30 disposed about the chimney, which acts as a continuance of the staging provided by the step 40 and other step members 30. Work platforms 40 are provided at stations B and C in connection therewith, said platforms being secured to the steps 30" or, as are the steps 30, telescoped over the band 3.

Fig. 3 is similar to the described form of my invention with the exception that a pair of overhead bridge members or like carrying structures are provided in lieu of the single structure shown in Figs. 1 and 2.

While I am aware that numerous and extensive departures can be made from the scope of my invention herein described and claimed without departing however from the spirit of my invention and the scope of the appended claims, I claim:

1. An obstruction lighting structure comprising a lamp supporting member, said member having a substantially long leg and a relatively shorter leg, said legs being connected by a concave loop portion, said relatively longer leg being disposed vertically of an upright cylindrical work structure and adapted to be securely locked to said work structure by means of a pair of bands telescoped over said work structure and securely locked therewith, said longer leg portion having a locked end portion adapted to be bent into locking engagement with the lowermost of said cylindrical bands and the relatively shorter leg having an upwardly bent portion, a lamp base being securely affixed thereto, said lamp base adapted to support a pair of electrical lamps whereby said lamps are secured to said work structure at a point spaced outwardly therefrom, a circular guard rail adapted to be secured to said hooked end portion of said relatively shorter leg, said guard rail being secured to said work structure by means of said lamp supporting member and by means of concave loop reinforcement members further secured to said work structure, a platform secured to the cylindrical work structure and disposed adjacent the lowermost end portion of said relatively longer leg.

2. An obstruction lighting structure comprising a lamp supporting member, said member having a substantially long leg and a relatively shorter leg, said legs being connected by a concave loop portion, said relatively longer leg being disposed vertically of an upright cylindrical work structure and adapted to be securely locked to said work structure by means of a pair of bands

telescoped over said work structure and securely locked therewith, said longer leg portion having a locked end portion adapted to be bent into locking engagement with the lowermost of said cylindrical bands and the relatively shorter leg having an upwardly bent portion, a lamp base being securely affixed thereto, said lamp base adapted to support lighting fixtures whereby said lighting fixtures are secured to said work structure at a point spaced outwardly therefrom, a circular guard rail adapted to be secured to said hooked end portion of said relatively shorter leg, said guard rail being secured to said work structure by means of said lamp supporting member and by means of concave loop reinforcement members further secured to said work structure.
